UNITED STATES PATENT OFFICE.

EDWARD J. NOBLE, OF NEW YORK, N. Y.

FELTING DEVICE.

1,145,917.

Specification of Letters Patent. Patented July 13, 1915.

Application filed May 4, 1912. Serial No. 695,020.

To all whom it may concern:

Be it known that I, EDWARD J. NOBLE, a citizen of the United States, residing at New York, in the county of New York and State 5 of New York, have invented certain new and useful Improvements in Felting Devices, of which the following is a specification.

This invention relates to the felting or 10 transferring of material composed mainly of wood pulp and diffused in water from such fluid medium to molds upon which the felted layer is shaped and afterward appropriately treated.

15 The purpose of the invention is to assist in the production of the body of a hollow container which is substantially of the shape of the frustum of a cone. The material of which the container is to be made is wood 20 pulp, or similar fiber, diffused in water with or without an admixture of other ingredients. It is intended that from this mass of pulp there shall be picked up a certain quantity of material which shall be automatically transferred to the inner member 25 of a mold upon which the body of the container shall afterward be formed and treated.

In the drawings Figure 1 is an end elevation 30 and partial vertical section of a device embodying the invention; Fig. 2 is a longitudinal vertical section on a plane at right angles to the section plane of Fig. 1; Fig. 3 is a vertical section on the plane of the line 35 3—3 in Fig. 2; Fig. 4 is a detail in section on the plane of the line 4—4 in Fig. 3, and Fig. 5 is a detail of the fluid seal between the outer edges of the transfer drum sections.

40 In the drawings 10 is a reservoir or tank of any suitable size, shape or material and open at the top. It is provided with a vertically placed partition 11 which extends above the top of the tank and which is in turn provided with a suitable aperture indicated at 12 to communicate with a drainage conduit 13 leading out of the tank. It is also provided with an aperture indicated at 14 and leading to a suitable vacuum producing means as an exhaust fan or blower 45 (not shown).

Mounted to rotate in suitable bearings formed in the sides of the tank 10 is a shaft 20 rotated from a suitable source of power (not shown) and rigidly secured to the shaft by any suitable means, as a key 21, is

a drum 22 in the general shape of the frustum of a cone and having one end closed by a partition 23 and its opposite end open and provided with a peripheral flange 24, 60 the edge of which is adapted to revolve in contact with the partition 11. The curved surface of the drum is made of any suitable foraminous material for instance woven wire fabric 25. Over this is placed a peculiar elastic surface made by winding spirally around the drum tubing made of coiled wire 26 and preferably somewhat elliptical in its coils. The coils are intermeshed as indicated in Figs. 2 and 5, so as 65 to form over the entire surface of the drum an even elastic but strong mat or cover, expanded or of open-work construction, so as to provide fluid passages therethrough longitudinally and transversely, as well as 70 from the inside to the outside. Over this surface is placed a somewhat loosely woven blanket 27. The drum is radially divided into sections or compartments by means of radial partitions 28 and at the end of 75 each partition and arranged transversely across and between the coiled wires is arranged a fluid seal made of soft rubber 29 or other suitable material, to prevent the passage of air from one drum compartment 80 to another longitudinally of the expanded cover. Arranged above the drum 22 and adapted to revolve in contact therewith is the inner member 30 of a mold, which is mounted upon a shaft 31 driven from a 85 source of power (not shown). Arranged at one side of the drum 22 is a revolving brush 35 having a cylindrical body 36 the interior of which is connected to a vacuum producing means as an exhaust fan (not shown) 90 by means of a conduit 37.

In the operation of the device the tank 10 is filled with water in which is diffused the wood pulp, with or without other materials. The drum 22 being rotated, a certain portion 100 of the pulp in the water clings to its blanketed surface, the water passing into the interior of the drum and out through the drainage conduit 13. In the meantime a partial vacuum is produced in the conduit 14. As 105 the sections of the drum arrive in turn opposite the opening of this conduit, such partial vacuum tends partially to dry the pulp adhering to the cylindrical segments from which the air is thus exhausted. The sealing material 29 prevents the air from leaking laterally from one compartment to an-

- other whereby the creation of a partial vacuum in a compartment as it rises from the tank is made possible. The drum continuing to revolve, the pulp on its surface is next brought into contact with the mold 30, and then transferred to said mold. The elasticity of the woven wire surface of the drum and its coiled wire cushion and outer blanket is sufficient to effect this transfer.
- 10 Any number of layers of the material may be rolled against and transferred to the mold. The drum continues to revolve and its surface is cleaned by the brush 35 in combination with the air exhaust in its cylinder which tends to remove from the drum any particles of the pulp which may yet adhere to it.
- What I claim is:
1. In an apparatus of the character described, a drum having a body of foraminous material in combination with an outer layer of intermeshed coiled wire.
  2. In an apparatus of the character described, a drum having a body of foraminous material in combination with an outer layer of intermeshed coiled wire spirally wound around the foraminous material.
  3. In an apparatus of the character described, a drum having a body of foraminous material in combination with an outer layer of intermeshed coiled wire and a further outside surface of blanket.
  4. In an apparatus of the character described, a drum having a body of foraminous material in combination with an outer layer of intermeshed coiled wire spirally wound around the foraminous material and a further outside surface of blanket.
  5. In an apparatus of the character described, a drum of woven wire or similar material, and an elastic body formed thereon by spirally winding coiled wire around the same.
  6. In an apparatus of the character described, a drum of woven wire or similar material, an elastic body formed thereon by spirally winding coiled wire around the same and intermeshing the adjacent spiral coils.
  7. In an apparatus of the character described, a drum of woven wire or similar material, an elastic body formed thereon by spirally winding coiled wire around the same and an outer layer of blanket or similar textile material.
  8. In an apparatus of the character described, a drum of woven wire or similar material, an elastic body formed thereon by

spirally winding coiled wire around the same and intermeshing the adjacent spiral coils and an outer layer of blanket or similar textile material.

9. In an apparatus of the character described, a drum having a body of foraminous material in combination with an outer layer of intermeshed coiled wire and one or more longitudinal ribs of fluid sealing material arranged within the wire layer.

10. In an apparatus of the character described, a drum having a body of foraminous material in combination with an outer layer of intermeshed coiled wire spirally wound around the foraminous material and longitudinal ribs of fluid sealing material arranged across the spiral windings.

11. In an apparatus of the character described, a drum of woven wire or similar material, an elastic body formed thereon by spirally winding coiled wire around the same and sheets of elastic fluid sealing material arranged transversely of the spiral coils.

12. In an apparatus of the character described, a drum of woven wire or similar material, an elastic body formed thereon by spirally winding coiled wire around the same and sheets of soft rubber arranged across the coils.

13. In combination, a tank, a partition therein extending outside of the tank, a drainage conduit leading from the partition, a drum closed at one end and adapted to contact with the partition at its opposite end, and means for dividing the drum into sectors and means for cleaning the outer surface of the drum, including a brush and means for connecting the interior of the brush with vacuum producing means.

14. In combination, a tank, a partition therein extending outside of the tank, a drainage conduit leading from the partition, a drum closed at one end and adapted to contact with the partition at its opposite end, and means for dividing the drum into sectors and a mold adapted to be revolved in contact with the drum and means for cleaning the outer surface of the drum, including a brush and means for connecting the interior of the brush with vacuum producing means.

In testimony whereof I affix my signature in presence of two witnesses.

EDWARD J. NOBLE.
